FIG. 1013.

FIG. 1.

FIG. 2.

FIG. 3.

R. H. N. Bates' Design for Stoves.
Patented June 9, 1858.

Dec. 1013

R. H. A. Bates, of Providence R. I.

Assign to himself:

Isaac Backus, of Canterbury Conn. & J. P. Baetow, of Norwich Conn.

Letters Patent No. 1013. Dated June 8th 1858.

The schedule referred to in these Letters Patent and making part of the same.

To all whom it may concern:

Be it known that I, R. H. A. Bates, of the City and County of Providence, and State of Rhode Island, have produced a new and ornamental Design for the doors of Cooking Stoves, and I do hereby declare that the following is a full, clear, and exact description of the same: reference being had to the annexed drawings, making a part of this Specification,

Figure 1. is a front view of the fire and draft doors of a cooking stove.

Figure 2. is a view of an oven door of ditto.

Figure 3. is a view of the door at the side of the fire chamber.

Similar letters in the figures refer to corresponding parts.

This design consists in forming around the edges of the door plates of Stoves, and outside the moldings of square or oblong frames, a continuous vine, or branch A, in Alto-relevo, similar in form to a series of Cima-reversas, and Cima-rectas, brought together, and continuing in the same style a smaller branch B, extending eccentrically from the segments of the circles of the said Cima-reversas and Cima-rectas, & in diverse directions, and terminating in a cone D.

Inside and outside this alto-relevo border, are moldings E, E, &

Des. 1013

a short distance within the inner one is a circular convex and angular molding combined, (G), which forms the panel H, whose surface is raised or extended beyond the plane of the border part of the plate. On the surface of this panel are formed in alto reliefs a series of Oak branches I, entwined in such a manner as to correspond with the simple order or style of the border, and having acorns on the ends of the smaller curved branches, which are extended from the main stems in such relative positions, distances and numbers, as to display the same simplicity of configuration as that represented in the border, and thus cause this center series of elaborately curved branches to harmonize with the other parts.

These center configurations are slightly modified when the space or panel in which they are formed is contracted, as on the smaller fire draft & side doors K, L, M, represented in figures 1 & 3. In these cases the panel work is simplified as represented in the figures just mentioned, in order to preserve the order and harmony aimed at in the combination of the several configurations & moldings of the plate.

What I claim as new and desire to secure by Letters Patent is—

Forming configurations and moldings on the door plates of stoves of the styles & form described, for the purpose of giving a simple and chaste ornamental appearance to the same.

Ex'd
